UNITED STATES PATENT OFFICE.

CHARLES EDWIN HAMILTON, OF TROY, NEW YORK.

IRONING MACHINE.

Application filed February 1, 1922. Serial No. 533,169.

To all whom it may concern:

Be it known that I, CHARLES EDWIN HAMILTON, a citizen of the United States, and a resident of Troy, in the county of 5 Rensselaer and State of New York, have invented certain new and useful Improvements in Ironing Machines, of which the following is a specification.

The invention relates to ironing pads as 10 employed in ironing tables for pressing or in an ironing machine; and more particularly to the coils or springs such as are shown in the resilient pad set forth in U. S. Letters Patent No. 1,054,407, granted me 15 the 25th day of February, 1913.

The pad disclosed in said patent consists substantially of a base plate upon which are secured a plurality of adjacent and helically coiled springs, the latter being 20 covered by suitable caps which support a fabric top. In the use of these springs, particularly with pads of inclined or cylindrical shape, difficulty has been experienced in retaining the frictionally held caps to 25 the spring ends; and, when a bottom cap is also employed, of retaining the spring in the said bottom cap. In a co-pending application for U. S. Letters Patent, Serial No. 460,696, filed April 12th, 1921, I have 30 closed means for rendering accidental displacement of the caps less likely to occur; but I have since found that, if the coils be constructed in manner hereinafter set forth, the caps may be entirely dispensed with.

35 In the accompanying drawings which illustrate the invention—

Fig. 1 is a sectional view of a cylindrical type of pressing machine provided with the resilient ironing pad which comprises 40 springs without any caps whatsoever.

Fig. 2 is a fragmentary perspective view of the improved form of cap.

Fig. 3 is a fragmentary sectional view, illustrating the manner of securing the caps 45 to a base plate.

Fig. 4 illustrates a modification.

Similar characters of reference designate corresponding parts thruout the several views.

50 Referring to the drawings, the pad may be of various shapes, for example cylindrical as is illustrated in Fig. 1; and it is this type of machine that is likely to introduce difficulty in the use of capped springs. In

55 accordance with the present invention, however, both the base and top caps are en-

tirely dispensed with, the pad being composed of a base plate 10 to which are secured in any suitable manner, for example by means of grommets 11 (Fig. 3), a plurality of springs 12, the inner edge of a grommet encircling the innermost convolution of a spring. This convolution may be of lesser diameter than the body of the spring, as shown in Fig. 3; or, may be of 60 the same diameter, as shown in Fig. 4. However, in accordance with the invention, the outermost convolution 13 is reduced in diameter, being of lesser diameter than the body portion of the spring. This will afford a sufficiently closed surface at the top for supporting the fabric 14, or the like, over the springs which are staggered and located closely together to afford a proper surface for ironing.

The tapering off of the upper end of the springs thus eliminates the caps heretofore employed; and, similarly, by employing grommets to secure the inner end of a spring to the base plate 10, the base caps 65 may also be eliminated, thus facilitating assembly of the pad as well as reducing the cost thereof and obviating the objectionable feature of the spring becoming separated from its caps.

I claim:

1. A unitary resilient supporting member for use with an ironing pad, comprising a supporting base plate, and a plurality of springs rigidly secured at one end to the 90 plate over the surface thereof, the other end of the springs being free and adapted to support the pad.

2. In an ironing pad support member of the character described, a base plate, and 95 a helically coiled spring having its innermost convolution of lesser diameter than the body of the coil and secured to the base plate.

3. A support member for an ironing pad 100 of the character described, comprising a perforated base plate, a helically coiled spring registering with a perforation thereof and having its outermost convolution of lesser diameter than the body of the coil to receive 105 and support the pad, and a grommet passing thru the perforation to secure the innermost convolution of the spring to the base plate.

4. A support member for an ironing pad 110 of the character described, comprising a base plate, a helically coiled spring having its

outermost convolution of lesser diameter than the body of the coil to receive and directly support the pad and its innermost convolution secured to the base plate.

5. A support member for an ironing pad of the character described, comprising a base plate, a helically coiled spring having its outermost convolution of lesser diameter

than the body of the coil to receive and directly support the pad and its innermost convolution of lesser diameter than the body of the coil and secured to the base plate. 10

Signed at Los Angeles in the county of Los Angeles and State of California this 23rd day of January A. D. 1922.

C. EDWIN HAMILTON.
